[57] CLAIM

The ornamental design for a plumb bob supporting vertical alignment gauge or the like, as shown.

DESCRIPTION

FIG. 1 is a top perspective view of a plumb-bob supporting vertical alignment gauge or the like showing my new design;

FIG. 2 is a front elevational view thereof;

FIG. 3 is a side elevational view thereof, the opposite side being substantially a mirror image; and

FIG. 4 is a rear elevational view thereof.

FIG. 1

FIG. 2

FIG. 4
